UNITED STATES PATENT OFFICE.

CHARLES F. MORSE, OF SOMERVILLE, MASSACHUSETTS.

ROLLER-SKATE.

SPECIFICATION forming part of Letters Patent No. 298,110, dated May 6, 1884.

Application filed February 5, 1884. (No model.)

To all whom it may concern:

Be it known that I, CHARLES F. MORSE, of Somerville, in the county of Middlesex and State of Massachusetts, have invented certain 5 Improvements in Roller-Skates, of which the following is a full, clear, and exact description, reference being had to the accompanying drawings, making part of this specification, in which—

10 Figure 1 represents a pair of skate-rollers with their connecting-axle constructed in accordance with my invention and applied to one of the bearings on the under side of a skate, one roller being in section and the other in elevation. Fig. 2 is a perspective view of my axle; Fig. 3, a perspective of the adjustable journal which screws thereon. Fig. 4 represents the key by which the said journal, when adjusted, is locked upon the end of the 15 axle. Fig. 5 is a perspective of one side of the box, located in the wheel in which the axle-journal bears. Fig. 6 is an elevation of the other side of the said box. Figs. 7 and 8 are elevations of the opposite sides of the outer 20 face-plate, which holds the journal-box in place within the wheel. Fig. 9 is a view of one side of the inner face-plate, by which the journal is retained within the wheel-box. Fig. 10 is a view of the opposite side of said inner plate. 25 Fig. 11 is a section representing the lubricating-passages. Fig. 12 is a section through the spring-actuated pin for keeping the outer face-plate in place; Fig. 13, an elevation of the inside of the wheel with its box and plates re- 30 moved. Fig. 14 is a view of the spanner-wrench which I employ in securing the parts together or in detaching them.

This invention relates exclusively to the construction and manner of connecting a pair of 35 skate-rollers with their axle. The ordinary way of securing such rollers is by the passage through the holes centrally made in the wooden rollers of an axle-bolt having a head at one end and a slot in the other for the reception of a bent retaining-wire. This construction is objectionable, for the reasons that the oil used for lubricating is free to escape outside through the central hole in the roller, and soils the dress of the skater. The dress also catches 40 against the projecting end of the axle-bolt and its retaining-pin. Said projecting end and pin under one skate are liable to strike against the

corresponding portions of the axle under the other skate of the pair on the feet of the skater. The dirt is sure to accumulate around the axle 55 and grind and wear away the bearing in the wheel, and enlarge the hole therein so rapidly that the axle and wheels play too loosely on each other, and it is difficult to remove the retaining wire or pin when the parts are to be 60 separated to clean them.

To overcome these objections is the purpose of my present invention, which consists in a wheel having a metal box for the reception of a journal, which screws on a threaded end of 65 the axle, and is locked thereto by a key when adjusted, a smooth metal face-plate flush with the outside of the wheel being employed to hold the journal-box therein, and an inner face-plate to retain the journal within its box, by 70 which construction oil is entirely or in a great measure prevented from escaping from the wheel. No projections exist for the dress to catch against. Dirt is precluded from entering the journal-box; the rattling of the parts 75 avoided, the friction reduced to the minimum, and the wear readily compensated by the adjustable journal.

To enable others skilled in the art to understand and use my invention, I will proceed to 80 describe the manner in which I have carried it out.

In the said drawings, A represents a wooden roller, having a cylindrical hole, *a*, passing centrally through it, Fig. 13, and provided 85 with an inner and an outer annular shoulder, *b*, the said hole being for the reception of a journal-box, B, Figs. 1, 5, and 6, having an inner annular flange, *c*, of considerable diameter let into the inner face of the wheel, and for a smooth 90 plate, C, Figs. 1, 7, and 8, fitted in flush with the outside of the wheel, the outside of the journal-box screwing into the turned-down portion *d* of the interior of the outer face-plate, C, by which means they are both retained in 95 their proper positions in the wheel.

e is a circular hole made through the outer face-plate, C, for the reception of a spring-actuated pin, *f*, located in a hole, *g*, in the contiguous portion of the wooden roller A, when 100 the hole *e* in the plate is brought in line with the pin after the plate has been turned sufficiently to draw the journal-box B into the desired position in the wheel, the pin preventing

the revolution of the plate C and its unscrewing and separation from the journal-box. The journal-box is also prevented from turning accidentally and unscrewing from the outer face-plate, C, by headed pins *h*, which pass through the flange *c* of the journal-box B into holes *i*, made in the adjacent inner surface of the wheel. D, Fig. 2, is the axle, each end of which has a screw-thread, *k*, cut thereon, over which turns a screw-threaded hollow journal, *l*, Fig. 3, provided at its inner end with an annular flange, *m*, which fits into a shouldered recess, *n*, of the journal-box, Fig. 5. The outer end of the axle is provided with a rectangular notch, *p*, and the annular wall of the corresponding end of the journal is also provided with two notches, *q*, of similar width, diametrically opposite each other, the notches in the journal and axle being for the reception of a key, *r*, Fig. 4, for locking them together, when so adjusted as to bring the inner side of the flange *m* of the journal against the outer side of an inner face-plate, E, and cause the latter to abut against the contiguous end of the bearing G of the axle on the under side of the skate, the inner face-plate, E, being provided with a number of slots, *s*, corresponding to those of the headed pins *h*, each slot having an enlarged portion, *t*, to admit of the plate being fitted upon the flange *m* of the journal-box, after which said plate is turned a partial revolution by a short projection, *u*, till the plate passes under the heads of the pins *h*, and a notch, *v*, in the periphery of the plate is brought in line with a spring-actuated pin, *w*, located in a hole, *x*, in the inner surface of the wheel, and passing through a hole, *y*, in the flange *m* of the journal box, whereby the inner plate is prevented from turning and the wheel from being detached from its journal, the distance between the two inner face-plates, E, corresponding to the distance between the ends of the axle-bearing G on the under side of the skate.

To lubricate the journals of the axle, an oil-passage, *z*, is provided, said passage extending from the outside of the inner face-plate, E, through the flange *m* of the journal-box B, through the latter to the journal *l*, whereby the lubricant is conducted to the surfaces,

where the greatest friction occurs, the outer 50 end of the journal-box being closed to preclude the escape of the same and soiling the dress of the skater.

To remove the parts, when the journals are to be adjusted to compensate for the slight 55 wear resulting by continued use, or for other purposes, I employ a spanner-wrench, H, (of the form seen in Fig. 14,) having two projections, 15 16, the longer one of which enters the hole *c* in the outer plate, C, occupied by the 60 pin *f*, which is pressed in against the resistance of its spring, thus permitting the plate to be unscrewed from the journal-box, the inner face-plate, E, being unlocked after pressing the spring-pin *w* out of the notch *v*. 65

The outer face-plate, C, may be provided with a central hole, and the journal-box *l* be lengthened, so as to extend therein; but in such case the outer surfaces of both would be continuously smooth and flush with each other to 70 avoid the existence of objectionable projections.

I claim—

1. An axle, D, having screw-threaded ends, 75 journals *l*, capable of adjustment thereon, and a means of locking them thereto, in combination with a pair of rollers, A, having journal-boxes B, and a means of securing them therein, constructed to operate substantially as and for the purposes described.

2. An axle, D, having its ends provided with screw-threads *k* and notches *p*, in combination with notched journals *l*, adjustable thereon, and keys *r*, for locking them thereto, as set forth. 85

3. A roller, A, having a journal-box, B, and an outer face-plate, C, for retaining it therein, an axle, D, having screw-threaded ends, a journal capable of adjustment thereon, and an inner face-plate, E, for locking the roller upon 90 the journal, as and for the purpose specified.

Witness my hand this 31st day of January, 1884.

CHAS. F. MORSE.

In presence of—

N. W. STEARNS,
ENOCH R. MORSE.
